W. P. Pitt

HINGE MECHANISM FOR BINDER COVERS AND THE LIKE

Filed Sept. 19. 1921

Inventor
William P. Pitt
By Warren H. House,
His Attorney

UNITED STATES PATENT OFFICE.

WILLIAM P. PITTS, OF KANSAS CITY, MISSOURI, ASSIGNOR TO IRVING-PITT MANUFACTURING COMPANY, OF KANSAS CITY, MISSOURI, A CORPORATION OF MISSOURI.

HINGE MECHANISM FOR BINDER COVERS AND THE LIKE.

Application filed September 19, 1921. Serial No. 501,525.

To all whom it may concern:

Be it known that I, WILLIAM P. PITTS, a citizen of the United States, residing at Kansas City, in the county of Jackson and 5 State of Missouri, have invented a certain new and useful Improvement in Hinge Mechanism for Binder Covers and the like, of which the following is a specification.

My invention relates to improvements in 10 hinge mechanisms for binder covers and the like. It is particularly well adapted for hinging covers of loose leaf binders or books.

One of the objects of my invention is 15 to provide a hinge mechanism which is simple, cheap to make, durable and strong and not liable to get out of order.

A further object of my invention is to 20 provide a novel pintle barrel for a cover combined with cheap and efficient means for securing the same to the cover.

Still another object of my invention is to 25 provide a novel pintle having means which permits its insertion into a barrel but which holds the pintle from withdrawal accidentally.

The novel features of my invention are hereinafter fully described and claimed.

In the accompanying drawing which 30 illustrates the preferred embodiment of my invention,

Fig. 1 is a plan view, partly broken away and partly in section of a binder member and cover connected together with my improved hinge mechanism.

Fig. 2 is a perspective view of one of the caps and a pintle mounted in the barrel thereof.

Fig. 3 is a cross section on the line 3—3 40 of Fig. 1.

Fig. 4 is a perspective view partly broken away and partly in section of one of the covers.

Fig. 5 is a plan view, partly broken away 45 and partly in section of a binder member and cover provided with a modification of my invention.

Fig. 6 is a cross section on the line 6—6 of Fig. 5.

50 Similar reference characters designate similar parts in the different views.

1 designates a clamping member of a loose leaf binder having fitted on its ends respectively two caps 2, preferably of metal and

provided each at one side with a pintle 55 barrel 3.

4 designates the body of a cover having in its inner end edge a groove 5 in which is mounted a pintle barrel 6 disposed between and alining with the barrels 3. 60

7 designates two pintles which extend respectively through the barrels 3 and into the cover barrel 6. The latter is secured in operative position by a sheet of binding material 8, which embraces the barrel 6 and 65 is secured to opposite sides of the body 4.

Each pintle 7 may be provided at its outer end with a head which bears against the adjacent barrel 3. Each pintle 7 is provided with an annular peripheral shoulder 9 disposed near the inner end of the pintle, the latter being, preferably, tapering. The barrel 6 is provided with two inwardly extending projections comprising, preferably, resilient tongues 10 which are 70 adapted to respectively engage the outer sides of the shoulders 9 for holding the pintles from accidental withdrawal from the barrels in which they are located. The shoulders 9 are preferably formed by cutting in the pintle an annular recess 11, which forms an inwardly tapering portion on the pintle and which at its inner end terminates in the abrupt shoulder 9. 75

The tongues 10 are preferably formed 80 by being punched inwardly from the barrel 6.

In assembling the parts, the caps 2 having been applied to the binder member 1, and the barrel 6 having been mounted in the 85 inner end of the cover, as described, the cover is applied to the binder member 1 with the barrel 6 alining with the barrels 3, after which the pintles 7 are slipped respectively through barrels 3 into the barrel 6. When the heads of the pintles bear against the barrels 3, the shoulders 9 will have passed inwardly beyond the tongues 10 respectively. The tongues 10 will spring into the recesses 11, and by engaging the 90 shoulders 9 will hold the pintles 7 from accidental withdrawal. 100

With the employment of my invention, a considerable saving may be effected in material for making the pintles, and riveting of the ends of the pintle is dispensed with. 105

In Figs. 5 and 6, I have illustrated a modified form of cover barrel comprising

- a U-shaped member 12, the arms of which respectively embrace the body 4 of the cover at the inner end thereof, a space being provided between the member 12 and the inner edge of the body 4 for receiving the pintles 7. The sheet of binding material 8 embraces the barrel member 12 and is secured to opposite sides of the body 4. Each arm of the member 12 may be provided with inwardly extending projections 13 which enter the body 4, for more securely holding the member 12 on the body 4. The binder member 1 is provided with a cap 2 at each end having the pintle barrel 3 through which extends the adjacent pintle 7, in the manner already described. The pintle 7 extends into the adjacent end of the member 12, and the latter is provided with two inwardly extending tongues 14 arranged to respectively enter the recesses 11 of the pintles and to respectively engage the outer sides of the shoulders 9 of the pintles in the same manner as was described with reference to the form shown in Fig. 1.
- 25 I do not limit my invention to the structure shown and described, as many modifications, within the scope of the appended claims may be made without departing from the spirit of my invention.
- 30 What I claim is:—
1. In a device of the kind described, two members, one having a pintle barrel, the other being a cover member provided with a body, a barrel mounted on the body at one end thereof and binding material embracing the last named barrel and secured to opposite sides of the body, the cover barrel having an inwardly extending projection, and a pintle mounted in said barrels and having a peripheral shoulder against the outer side of which said projection is adapted to bear, substantially as set forth.
  2. In a device of the kind described, a member having at one end a cap having at one side a pintle barrel, a cover member having at one end a barrel provided with an inwardly extending projection, and a pintle mounted in said barrels and having a peripheral shoulder against the outer side of which said projection is adapted to bear, substantially as set forth.
  3. In a device of the kind described, two members one having a pintle barrel, the other being a cover member having a body, a pintle barrel at one end of the body, and binding material embracing the last named barrel and secured to the body, and a pintle in said barrels having an annular peripheral shoulder, the cover barrel having a resilient inwardly extending tongue adapted to bear against the outer side of said shoulder, substantially as set forth.
4. In a device of the kind described, a member having at one end a cap having at one side a pintle barrel, a cover member having a body, a pintle barrel at one end of said body, and binding material embracing the last named barrel and secured to the body, and a pintle in said barrels having a peripheral shoulder, the cover barrel having a resilient inwardly extending tongue adapted to bear against the outer side of said shoulder, substantially as set forth.
5. In a device of the kind described, a member having at opposite ends respectively two caps each having at one side a pintle barrel, a cover member having at one end a barrel between and alining with said barrels, the cover member barrel having two inwardly extending resilient tongues, and two pintles extending respectively through the first two barrels and into the cover barrel, each pintle having a peripheral shoulder, the two tongues being adapted to bear respectively against the outer sides of said shoulders, substantially as set forth.
6. In a device of the kind described, a leaf-clamping member having at one longitudinal edge a pintle barrel, a cover member adapted for swinging relationship to said clamping member and having at one edge a pintle barrel in alinement with the pintle barrel of the clamping member, and a pintle adapted to be mounted in one of said barrels and adapted for insertion in the other pintle barrel, the latter having means arranged to engage the pintle to hold the pintle from withdrawal therefrom, substantially as set forth.

In testimony whereof I have signed my name to this specification.

WILLIAM P. PITTS.
